UNITED STATES PATENT OFFICE.

JOSEPH F. BORST AND WILLIAM BORST, OF BROOKLYN, NEW YORK.

TABLE FOR TALKING MACHINES.

Application filed February 1, 1921. Serial No. 441,603.

To all whom it may concern:

Be it known that we, JOSEPH F. BORST and WILLIAM BORST, both citizens of the United States, and residents of the city of New York, borough of Brooklyn, in the county of Kings and State of New York, have invented a new and Improved Table for Talking Machines, of which the following is a full, clear, and exact description.

10 The present invention relates to new and useful improvements in talking machines, and it pertains more particularly to a new and improved construction of talking machine table.

15 We have found by actual experiment that the motor in its operation produces certain friction, vibration and sounds conveyed to the sound box by the various metal parts of the mechanism, and which are responsible to 20 a large extent for poor and improper reproduction on the part of the sound box.

25 We have also found that spring members used in talking machines do not rotate the table at a constant speed. This condition owing to the uneven movement between the record and the stylus, produces objectionable vibration, and sounds and noises which could be eliminated if the table were driven at constant speed.

30 It is, therefore, one of the primary objects of the invention to insulate the diaphragm from friction, vibration and sounds from the sound box and stylus and various metal parts of the machine. By so doing we 35 control friction, vibration and sounds to the greatest extent possible, thereby allowing vibration and harmony to act in its clearest state.

With the above and other objects in view, 40 reference is had to the accompanying drawings, in which—

Figure 1 is a sectional view of a talking machine table and sound box;

Fig. 2 is a detail top plan view partly in 45 section of a table constructed in accordance with the present invention;

Fig. 3 is a detail sectional view taken at the central portion of the table.

50 Referring more particularly to the drawings, the reference character 5 designates the motor spindle and 6 designates the table. Secured to the under face of the table 6, is a bearing member 7, and this bearing member is provided with a continuous channel 8 in its upper face. The bearing member 7 is 55 cut out as indicated by the reference char-

acters 9 and 10 for the reception of lead washers 11 and 12, respectively, and said member 7 is secured to the under side of the table 6 in any desired manner, such as by soldering, riveting, or the like, and before the same is positioned upon the under side of the table, the channel 8 is filled with mercury indicated by the reference character 13. By means of the lead washers 11 and 12, it will be seen that the member 7 and the spindle 5 will be insulated from the table 6 by these lead washers, which metal is known to have poor qualities for the transmission of friction, vibration and sounds. The mercury in the channel 8 serves as a counterbalance for the turntable, and owing to the mercury being mobile under the influence of the rotation of the table, the latter rotates at a constant speed.

As more clearly shown in Fig. 2, the table 6 is provided upon its upper face at its central point, with a depressed circular portion 15, and mounted in said depressed portion 15, is a suitable material 16, which has poor qualities for transmitting vibration and sound. We have found by experiment that sulphur serves this purpose best, and it is this material which is used, the same being heated to a plastic state and placed within the circular groove or channel 15. By reference to Fig. 3 of the drawings, it will be seen that this groove or channel 15 is concentric with the channel 8 in which the mercury 13 is carried, and that the sulphur 16 is 90 immediately above the mercury 13. Branching off from this circular portion 15 of sulphur 16, at equidistantly spaced intervals, are legs 20, and said legs 20 are formed from sulphur, the table being depressed as indicated by the reference character 21 in order that the sulphur 16 may be more securely carried by the table. After the central circular member 15 and the radial legs 20 have been formed, the entire table is covered with 95 felt or the like 25, as is the common practice.

Referring to Fig. 1, the reference character 30 designates the sound box and 31 designates the diaphragm thereof. This diaphragm is mounted in the sound box 30 between the two circular rings 32 of sulphur, it being understood that the diaphragm 31 does not contact directly with the rings of sulphur 32, there being a suitable thickness of felt interposed between the diaphragm 110 and the rings 32 upon each side of the diaphragm. Extending from the rear of the

sound box 30, is a tone arm 33, and said tone arm 33 is flanged as at 34 to provide for its attachment to the rear wall of the sound box. Interposed between the flange 34 and the 5 rear wall of the sound box 30, is a sulphur washer, and upon opposite sides of said sulphur washer are disks 36 of felt or the like. If any screws be present to hold the sound box to the tone arm, we insulate the same by 10 felt washers or the like.

The reference character 40 designates the stylus bar pivotally mounted as at 41 to the sound box 30, and having its innermost end rigidly secured to the diaphragm as at 42. 15 The common practice of securing the stylus bar 40 to the diaphragm 31, as by means of a rivet or the like, which we line with felt, but in the present instance in order that the diaphragm may be thoroughly insulated, the 20 inner end of the stylus bar is secured to the diaphragm by means of sulphur, it being understood that the sulphur is heated and applied in a plastic state.

From the above it will be apparent that 25 the friction and the vibration generated in the motor during the operation thereof, are insulated from the record tablet (the same being indicated by the reference character B), by reason of the fact that the tablet is 30 supported upon the legs formed of the sulphur 16 and out of communication with the table 6. The construction of the table mounting, i. e., the bearing member 7 with the lead washers 9 and 10, also serves to insulate the table to a certain degree from the 35 friction and vibration generated in the motor.

The noises and vibration of the motor which pass in the opposite direction and 40 through the tone arm 33, will be insulated from the sound box by means of the sul-

phur washer 35 interposed between the sound box 30 and the flange 34 of the tone arm 33.

The friction, vibration and sounds incident to the frictional contact of the stylus with the record will be prevented from being transmitted to the diaphragm 31 by reason of the sulphur 42 which secures the stylus bar to the diaphragm 31, and the diaphragm 31 is further insulated by means of the sulphur washers 32 between which it is mounted. We find that it is most capable for holding purposes in this position, as it is steadfast to weather, vibration and such, 55 as we well know rubber or the like being used in the same position is not steadfast to weather, vibration or the like.

From the foregoing it is apparent that all 60 of the metal parts of the reproducing mechanism of a talking machine constructed in accordance with the present invention are insulated one from the other by a suitable material, the transmission qualities of which are extremely low, which construction leaves 65 the diaphragm free from exterior friction, and sounds and permits the same to properly function and consequently render a clearer reproduction.

We claim:

In a talking machine, a record supporting table, a mount therefor, said mount comprising a bearing member for supporting said record table and secured to the under face thereof, a continuous circular groove formed 75 in the bearing member in its table engaging face, and mercury carried in said groove and freely movable with respect thereto, as and for the purpose set forth.

JOSEPH F. BORST.
WILLIAM BORST.
